UNITED STATES PATENT OFFICE.

CHARLES EDMUND CLEWS, OF PAEROA, AUCKLAND, NEW ZEALAND.

COMBINED WINDOW-SASH FASTENER, LIFTER, AND ANTIRATTLER.

1,275,531.

Specification of Letters Patent.

Patented Aug. 13, 1918.

Application filed November 11, 1915, Serial No. 60,894.

To all whom it may concern:

Be it known that I, CHARLES EDMUND CLEWS, a citizen of the Dominion of New Zealand, and residing at Paeroa, Auckland, 5 in the Provincial District of Auckland, in the Dominion of New Zealand, have invented certain new and useful Improvements in Combined Window-Sash Fasteners, Lifters, and Antirattlers, of which the following 10 is a specification.

The invention relates to an improved sash fastener or lock combining means for lifting or lowering and preventing rattling of sashes of windows, and more particularly 15 the invention relates to single sash sliding windows of any particular description.

An upwardly or downwardly sliding sash has a fastener and lifter combined made according to this invention affixed to the inner 20 face of each stile of the sash; each fastener and lifter combined being exactly alike, the one being turned upside down before being fixed without any alteration in construction; the sash thereby being held in any position 25 so that it cannot be raised or lowered until the fasteners and lifters are released. At the same time the fastener and lifter prevent the rattling of the sash in the frame. In the case of a horizontal sliding sash one 30 sash fastener and lifter is placed on the inside of the bottom or top rail of the sash; by which means the sash is locked in any required position, at the same time preventing rattling.

35 The invention comprises a casing or housing having a dome or hollow boss whereon the cam is pivoted. The edge of the cam is widened out or may be serrated to increase the grip. A coil spring passes around the 40 stud forming a continuation of the pivot of the cam; one end of the spring being fixed to the stud and the other end is attached to a projection or tail piece of the cam. A lug is formed integral with the casing forming 45 a sash lifter in conjunction with the tail of the cam and is operated by the pressure of the thumb and fingers.

In the drawings:—

Figure 1, is a front elevation,

50 Fig. 2, a side elevation, and

Fig. 3, a plan of the device fixed to the bottom corner of a window sash made to open upward.

Fig. 4, is a reverse elevation of the device.

Fig. 5, an elevation of the inner face of 55 a window sash, and

Fig. 6, an elevation of a horizontal sliding window showing the positions of the devices thereon.

The casing 1 has lugs 2 by which it is 60 secured to the stile 3 of the window sash. A dome or hollow boss 4 is cast, stamped or otherwise formed to receive a coil spring 5; one end of which is secured to the stud 6 and the other end passes through an opening 10 in the dome or boss 4, and is secured to the tail 7 of the cam 8, which is pivoted outside the boss 4 upon the end of the stud 6.

An arm 9 is formed integral with the dome or boss 4 and together with the elongated tail 70 piece 7 of the cam 8 forms the lifter.

The positions for fixing the devices are shown in Fig. 5 on a sash which opens upward, and in Fig. 6 on a horizontal sliding sash. In Fig. 5 the devices are fixed near 75 the bottom of the stiles of the sash; one on each side of the sash that on the one side being upside-down to that on the other side. The cams 8 grip against the jambs 11 and 12 of the window frame, the cam gripping 80 against the jamb 11 preventing the sash from being lowered after it has been raised and the cam gripping the jamb 12 preventing the sash from being raised from any position; both cams pressing against the jambs 85 preventing the sash from rattling. On the sash which opens downward the devices are fixed upon the stiles near the top of the sash as shown by dotted lines in Fig. 5, and the raising and lowering and rattling of 90 the sash is prevented in the same manner as when the devices are fixed on the lower end of the stiles of the sash.

On a sash which slides horizontally the device is placed on the bottom or top rail 95 of the sash and the cam presses upon the running strip of the frame 14 effectually locking the sash when it is closed or when the sash is placed in any predetermined position.

In operation, when it is required to raise or lower a sash or to slide a horizontal sash the arm 9 and the tail piece 7 are gripped by the fingers and thumbs, the tail piece 7 pressed toward the arm 9 withdrawing the grip of the cams 8 from the jambs 11 and 12 or running strip 14, the window sash can then be lowered or raised or in the case of a

horizontal sliding sash can be slid along. When the tail piece 7 is released the resiliency of the coil spring 5 presses the cam against the jambs and prevents the sash 5 being lowered, slid or raised as the case may be.

The cams 8 may have a serrated edge 13 to give an increased grip.

What I do claim and desire to secure by Letters Patent of the United States is:—

A device of the class described, consisting of a casing comprising a hollow boss having a portion of its side cut away to provide an opening, and having lugs for securing it to a window sash, a stud passing through said boss, a member exteriorly pivoted on said

stud, having an operating handle and having a cam surface adapted to engage the surface of a window jamb, a lifting member integral with said boss, a helical spring coiled 20 around said stud within the boss, having one end held by the stud and the other end extending through said opening in said boss and engaging said operating handle.

In testimony whereof I have signed my 25 name to this specification in the presence of two witnesses.

CHARLES EDMUND CLEWS.
